UNITED STATES PATENT OFFICE.

CHARLES DESOUTTER, OF LONDON, ENGLAND.

ARTIFICIAL LEG.

1,335,781.

Specification of Letters Patent.

Patented Apr. 6, 1920.

Application filed September 13, 1919. Serial No. 323,474.

To all whom it may concern:

Be it known that I, CHARLES DESOUTTER, a subject of the King of Great Britain and Ireland, residing at 51 Baker street, London, W., England, have invented certain new and useful Improvements in Artificial Legs, of which the following is a specification.

This invention relates to artificial legs, 10 and refers more particularly to the means of attaching the limb to the pelvic band.

With the ordinary method of attachment by means of a vertical strip or connection rod attached to the pelvic band which connection rod has pivoted thereto the strip or the like attached to the bucket of the leg, various drawbacks are apparent in practical use.

For instance it is difficult to move the 20 body freely from side to side when standing or sitting or to open or move the artificial leg, and the bearer is likely to become strained or to put a strain upon the band.

It is difficult to exchange one form of 25 connection rod for another and a large supply of bands and connection rods have to be kept in stock or considerable delay is occasioned in suiting the requirements of different wearers.

According to the general principle of my 30 invention I connect the connection rod to the pelvic band in such a way that it can be readily interchanged for a connection rod of a different size or length and so that it 35 can rotate around a substantially vertical axis.

I further so connect the metal band or strip carrying the attachment for the connection rod to the pelvic band, in such a way 40 that the said band or strip can be easily removed from the band or placed in position therein, so that it is easy to change the band and fitting for another, or to adjust or modify the position of the fitting.

In order that my said invention may be 45 more clearly understood I will now proceed to describe the same with reference to the drawing accompanying this specification in which:—

Figure 1 shows a front elevation, in the standing position showing an artificial leg, 50 with my invention applied thereto.

Fig. 2 shows a similar view to Fig. 1 illustrating the sitting position.

Fig. 3 shows a diagram of the vertical bearing and band.

Fig. 4 is a front elevation, and Fig. 5 a side elevation of one form of connection rod.

Fig. 6 shows an enlarged view of a portion of a pelvic band with my further improvements adapted thereto.

Fig. 7 shows the band and bearing for the connection rod attached.

Fig. 8 is a diagram showing the strip and bearing laced in position in the band. 65

The same letters of reference are employed to denote the same parts in all the views.

a is the artificial leg of any ordinary description, provided with the usual bucket. 70 *b* is the rod or strip by means of which it is carried. *c* is the pelvic band, which is provided in the present case with a vertical tubular bearing *d*. *e* is the connection rod, the portion *f* of which is adapted to be inserted into and work in the tubular bearing *d*. The portion *f* is provided with a screw threaded end upon which a nut *g* is adapted to screw when the parts are in position. 75

h is the eye plate for attachment to the 80 fork at the top of the member *b*.

In some cases the rod or strip *b* may be formed with the eye plate and the end of the connection rod may be forked, as at *h*. Fig. 2. 85

In all cases where found desirable, the connection rod may carry a forked connection.

Referring to Fig. 6 it will be seen that the pelvic band is made up from an inner band 90 *j*, and an outer band *k*, sewed together at the edges.

The band *k* is slit as shown at *m*.

The bearing *d* has attached thereto the curved plates or strips *p* and *q*, extending 95 at each side of the bearing or it is formed with or mounted upon a portion of the metal band *p* *g*.

This band *pq* is inserted through a slit *m* in the pelvic band, and the whole is then 100 fastened in position by means of the lacing *n*, thus allowing for adjustment and for replacing by another band.

Any additional padding or lining which may be required can be placed between the 105 bands *j* and *k*.

The various advantages accruing from the foregoing constructions may now be briefly examined.

It will be seen that from the connection rod 110 *e* fitting into the bearing sleeve or collar *d*, it is a very easy matter to replace a connec-

tion rod of one form or size, by a connection rod of another form or size, it being simply necessary to unscrew the nut *g* to remove the connection rod *e* and to replace it by another connection rod *e* of the required shape and size and then to restore the nut *g* to its original position.

Owing to the fact that the connection rod is carried from a pivot which is rotatable about a substantially vertical axis, it is possible for the wearer of the artificial limb to have considerable freedom, as compared with wearers of ordinary artificial limbs, as he can turn the limb to a considerable extent when it is in a vertical position, as illustrated at Fig. 2. In the latter case the leg can be opened out without difficulty, which is practically impossible with the ordinary constructions.

As regards the means of attachment of the bearing to the pelvic band, this also offers important advantages, as owing to the fact that the bearing is attached to metal strips, which are laced in position in the pelvic band it is a simple matter to change one band for another, so that a band suitable for any wearer may be adapted in a few minutes to any required bearer.

Moreover if there is any sore place made by the belt, as is often the case, with the ordinary constructions, the wearer has simply to unlace the belt and to place cotton wool or other suitable padding in the required position.

The belts can be made in large quantities in the first instance, thereby reducing the cost.

It will be understood that the particular details of construction can be varied considerably without departing from the principle of my present invention.

What I claim as my invention and desire to secure by Letters Patent of the United States of America is—

1. In combination an artificial leg having an upper leg section adapted to fit the stump of the thigh, a pelvic band or the like provided with a bearing, means for suspending the artificial leg from said band comprising a connection rod pivotally connected to said artificial leg at one end and mounted at its other end in said bearing for rotatable movement about a vertical axis.

2. Means for attaching the connection rod for an artificial leg to the pelvic band, consisting in attaching the bearing or joint for the connection rod to a strip or strips which are adapted to be inserted into and laced in position in the band, substantially as and for the purposes set forth.

3. In combination an artificial leg having an upper leg section adapted to fit the stump of the thigh, a pelvic band or the like provided with a tubular bearing, a connection rod adapted to be hingedly connected at one end to the upper leg section and at its other end to be passed through said tubular bearing, and means for retaining said last mentioned end in said bearing for rotatable movement about a substantially vertical axis.

4. In a device of the class described, a pelvic band having an opening therein, a bearing having a strip adapted to be inserted in said opening for attaching said bearing to said band, a connection rod adapted to be connected at one end to an artificial leg and at its other end connected to said bearing for rotation about a substantially vertical axis.

In testimony whereof, I have hereunto subscribed my name.

CHARLES DESOUTTER.
